(57) **CLAIM**

The ornamental design for a decorative panel for building as shown and described.

DESCRIPTION

FIG. 1 is a front view of the decorative panel shown in a condition of use, with the decorative panel being used in conjunction with a second broken line decorative panel; FIG. 2 is a front view of an embodiment of a decorative panel for building according to my new design; FIG. 3 is a left side view thereof;

FIG. 4 is a bottom perspective view thereof;

FIG. 5 is an enlarged, partial left side view of the building panel showing the portion within area 5 of FIG. 3; and, FIG. 6 is an enlarged, partial front view of the building panel showing the portion within area 6 of FIG. 2.

The faded portion surrounded by broken lines of FIG. 1 illustrates an additional panel that forms no part of the claimed design. The dot-dash lines of FIGS. 2, 3, 5 and 6 depict the boundaries of enlargement and form no part of the claimed design.
